UNITED STATES PATENT OFFICE.

ROY E. BROWN, OF PORTLAND, OREGON, ASSIGNOR OF ONE-THIRD TO GEORGE A. ALBRIGHT, OF PORTLAND, OREGON.

LOCK.

1,342,157.

Specification of Letters Patent.

Patented June 1, 1920.

Application filed July 31, 1919. Serial No. 314,491.

To all whom it may concern:

Be it known that I, ROY E. BROWN, a citizen of the United States, residing at Portland, in the county of Multnomah and 5 State of Oregon, have invented certain new and useful Improvements in Locks, of which the following is a specification.

This invention seeks to provide a simple and inexpensive lock of that type which do 10 not require the use of keys and by which the door may be freely opened from the inside and which also may be so arranged as to permit opening of the door freely from either side. The invention is primarily de- 15 signed for use upon swinging doors but is also applicable to sliding or folding doors and to the locks of trunks and similar receptacles. The invention is illustrated in the accompanying drawings and resides in 20 certain novel features which will be herein-after first fully described and then particularly pointed out in the appended claims.

In the drawings—

Figure 1 is an elevation of the lock with 25 one side of the casing removed and showing the bolt projected;

Fig. 2 is a similar view showing the parts arranged to permit opening of the door by a person outside the building;

Fig. 3 is a horizontal section on the line 30 3—3 of Fig. 1;

Fig. 4 is a view similar to Fig. 1 but showing the bolt retracted and showing the parts arranged to permit free opening of the door 35 from either side;

Fig. 5 is a view showing the lock casing in section and the tumblers in edge elevation;

Fig. 6 is a face view of so much of the lock casing as appears in Fig. 5.

The application of the invention to a 40 swinging door lock is illustrated in the drawings in which the reference numeral 1 indicates the lock casing and 2 the bolt slidably mounted in the upper portion of the casing. The bolt is provided with a reduced inwardly extending tongue 3 having a longitudinal slot 4 through which a knob spindle may extend from the inner side of the door and this spindle carries at its outer end a 45 crank or lever arm 5 which bears against an offset or lug 6 upon the tongue 3 whereby when the spindle is rocked the said crank or lever arm will cause the bolt to slide in-

wardly and permit swinging of the door, the projected and retracted positions of the bolt 55 being shown in Figs. 1 and 4, respectively. A knob 7 is secured on the inner end of the said knob spindle to facilitate its manipulation and a spring 8 is disposed within the upper portion of the casing and bears 60 against the inner end wall of the casing and against a shoulder 9 on the bolt so that by its expansion the spring serves to normally hold the bolt projected. To the under side of the bolt, I pivot one end of a hook 10 65 which has its beak 11 arranged to be engaged by a plurality of tumblers whereby, when the tumblers have been properly adjusted, rotation thereof will exert a pull through the hook upon the bolt to retract the 70 same. A stop latch 12 is carried by a stem 13 rotatably mounted in the inner face plate of the lock casing and upon the inner exposed end of said stem is a manipulating knob or handle 14. Normally the latch 12 75 will be swung upwardly, as shown in Figs. 1 and 2, but it may be swung down, as shown in Fig. 4, to bear upon the upper side of the hook 10 and thereby hold the same in its lowered position. The knob 80 spindle which carries the crank or lever arm 5 does not extend through the outer face plate of the lock casing so that it can not be manipulated from the outside of the door. To permit operation of the bolt from the 85 outer side of the door, I provide a tumbler shaft 15 which is journaled in the face plates of the lock casing and extends through the outer face plate to carry a knob or other handle 16 and secured upon the said shaft 90 to rotate with the knob 16 is a dial 17 carrying a scale of numerals or other indicating characters, the face plate of the lock casing being provided with an index 18 of any desired form arranged immediately adjacent 95 the edge of the dial 17 so that an authorized person knowing the combination to the lock may manipulate the dial to properly set the tumblers. In the illustrated embodiment of the invention, three tumblers 19, 20 and 21 100 are employed, the outer tumbler 19 being fixed to the tumbler shaft and the intermediate and inner tumblers 20 and 21 being loose upon the shaft. The tumblers are of identical construction, being each provided 105 in its edge with a substantially V-shaped

notch or recess 22 to receive the beak 11 of the hook 10 and lugs 23 being disposed upon the opposed faces of the tumblers to set the tumblers by being brought into contact 5 through manipulation of the handle or knob 16. Spacers 24 are fitted upon the tumbler shaft between the tumblers so as to hold them in the proper spaced relation and prevent frictional engagement between the tumblers 10 which might detract from the successful operation of the lock. The lugs 23 may, of course, be fixed upon the tumblers, but in order that the combination may be varied at the will of the owner, I prefer to employ 15 headed pins adapted to be inserted in any one of the series of openings or sockets 25 formed in the tumblers adjacent the peripheral edges thereof. It will be readily understood that the combination of the lock 20 may be readily changed by shifting the pins and setting them in different openings of the respective tumblers.

Upon reference to Fig. 1, of the drawings, it will be readily noted that the beak 11 will 25 ride upon the periphery of a tumbler unless said tumbler is so set that the notch therein will be below the beak and, consequently, the bolt may be freely retracted by the inner knob 7, but manipulation of the outer 30 knob 16 will have no effect upon the bolt unless the said knob is rotated in the proper direction and in the proper manner to bring the notches of all the tumblers into position below the beak whereupon the beak will 35 drop into the notches and rotation of the tumblers to the right will pull upon the hook so as to retract the bolt. To bring the notches of all the tumblers into alinement with each other and with the beak 11, as 40 shown in Fig. 2 the knob 16 must be rotated or rocked in a manner determined by the combination for which the tumblers have been set by the adjustment of the lugs 23. The outer tumbler 19 will always move with 45 the tumbler shaft to which the knob 16 is secured but the tumblers 20 and 21 will not move with the shaft unless the lug 23 of the tumbler 19 has been brought against the lug on the outer face of the tumbler 20 and the 50 shaft then rotated or rocked to bring the lug on the rear face of the tumbler 20 against the lug on the tumbler 21. It is obvious that continued rotation of the tumbler shaft in one direction will bring the lug 23 55 on the tumbler 19 against the lug on the front face of the tumbler 20 and then bring the lug on the rear face of the tumbler 20 against the lug on the tumbler 21, but such a simple manipulation of the tumbler shaft 60 will not bring the notches 22 into proper alinement. To bring the notches into the proper alinement, the tumblers must be set in the manner determined by the positions of the several lugs as will be readily understood. The initial rotation of the knob 16, 65

therefore, will continue until the inner tumbler 21 has been set with its recess or notch 22 under the beak 11 and this position of the tumbler will be denoted by the numeral or other character upon the dial 70 17 which represents the first element of the combination alining or registering with the index 18. The tumbler shaft is then rotated in the opposite direction so that the tumbler 21 will remain at rest and the lugs upon the 75 adjacent opposed faces of the tumblers 19 and 20 will be reengaged but with the lug upon the tumbler 19 at the opposite side of the lug upon the tumbler 20 from its former position. The tumbler 20 will then be actuated to bring its notch under the beak 11 which position will be indicated by the character denoting the second element of the combination registering with the index 18. The direction of rotation of the tumbler 80 shaft is then again reversed so that the recess of the tumbler 19 will be brought below the beak 11 whereupon the rotation of the tumbler shaft to the right will exert the required pull upon the hook 10 to retract 90 the bolt. It is to be noted that one wall of each notch or recess 22 is approximately radial so that it will have an abrupt engagement with the beak 11 and exert the desired pull thereon, but the other wall of the notch 95 is disposed at an angle to the radius and the inner surface of the beak is convex so that the rotation of the tumblers to the left will simply cause the beak to ride out of the notches. The index 18 may be a small rib or 100 groove in the face plate of the lock casing and for convenience, I have illustrated it as a slight groove or indentation, as clearly shown in Fig. 5. Opening of the door from within a room or building is not dependent 105 on the combination but is effected by merely rocking the knob spindle so that the crank 5 will assume the position shown in Fig. 4 and withdraw the bolt through engagement with the offset 6. Of course, if the spindle 110 be left in this position, the bolt will be held retracted inasmuch as the crank will be at a right angle to the plane of the offset or shoulder and the door may be opened freely from either side but as the spindle is apt 115 to be moved by chance contact with a passing object and the bolt thereby released, I provide the dead latch 12. When this latch is to be used, the combination must be worked so that the tumblers will be set to 120 withdraw the bolt and the latch will be swung down after the door has been opened. The latch will bear upon the hook so that it cannot rise from the notches 22 and clear the tumblers and, consequently, the bolt will be 125 held retracted.

From the foregoing description, taken in connection with the accompanying drawings, it will be seen that I have provided an exceedingly simple permutation mechanism 130

whereby a lock may be readily opened when the combination is known but cannot be opened by unauthorized persons.

Having thus described the invention, what is claimed as new is:

- 5 1. In a lock, the combination of a bolt, means for holding the bolt normally projected, a hook pivoted to the bolt, a plurality of tumblers disposed below the hook, means rear end with a depending beak, a plurality of tumblers mounted below the said hook 30 and provided with peripheral notches to be engaged by said beak, means for setting the tumblers whereby to bring the notches into alinement with each other and the beak, and means acting on the hook to hold the beak 35 in engagement with the notches after the bolt has been retracted.
- 10 2. In a lock, the combination of a bolt, means for holding said bolt normally projected, a hook pivoted at its front end to 40 said bolt near the front end thereof and having a depending beak at its rear end, a plurality of tumblers disposed below the bolt and the hook and having peripheral notches, projections on the opposed faces 45 of the tumblers, means for rocking the tumblers to effect engagement between said projections and set the tumblers with their notches in alinement with each other and with the said beak, and a manually operable 50 latch mounted between the bolt and the hook to bear upon the hook and hold the beak thereof in engagement with the notches of the tumblers.
- 15 3. In a lock, the combination of a bolt, means for holding said bolt normally projected, a hook pivoted at its front end to the bolt near the front end thereof and provided at its inner
